RUDDER FOR BOATS

Albert J. Dawson, Pittsburgh, Pa., assignor to
Dravo Corporation, Pittsburgh, Pa., a corpora-
tion of Pennsylvania

Application July 7, 1943, Serial No. 493,744

6 Claims. (Cl. 114—166)

This invention relates to the steering of boats and consists in improvement upon steering apparatus that includes a "Kort nozzle," whereby the boat is rendered more readily responsive to her tiller, particularly in backing.

The invention is illustrated in the accompanying drawings, in which:

Figure I is a view in vertical and medial section of the steering equipment of the invention in assembly upon the stern of a boat;

Figure II is a view of the steering equipment in elevation, as seen from astern and looking forward;

Figure III is a view in horizontal section, on the plane indicated by the broken line III—III, Figure II;

Figure IV is a sectional view, partly on the horizontal plane axial of the propeller shaft, partly on higher plane, and illustrates the ranges of swing of components of the equipment;

Figure V is a fragmentary view, in horizontal section, on the plane V—V of Figure I;

Figure VI is a top plan view of the stern of a ship with the rudder assembly; and

Figure VII is a view similar to Figure I, of a modified construction.

In the propulsion of boats it is a known expedient to enhance the effect of a propeller; and, incidentally, to shield and protect it, by encircling it within a ring properly shaped and proportioned. Such an encircling ring is shown and described in United States Letters Patent No. 2,030,375, granted to L. Kort. The ring is bullet-like and flares forwardly and rearwardly from a medial portion of minimum diameter; and, in cross-sectional shape, the ring walls are of streamlined or hydrofoil contour. The ring is so assembled with the propeller that the plane in which the tips of the propeller blades rotate is substantially coincident with the vertical diameter of the circle of the ring wall at its narrowest. Such a ring is known to the industry as a "Kort nozzle."

It is also a known expedient to mount such a propeller-encircling ring upon the rudder of the boat, and so to give to it additional functional value, as part of the steering apparatus. Such an arrangement is illustrated in Letters Patent No. 899,359, granted to Y. Wadagaki. It is upon such an organization that the present improvement is made.

Referring to the drawings, a pintle-hung rudder 1, having a Kort nozzle 2 integrated with it, is shown to be mounted upon the stern of a boat B. The rudder is so built that the axis of turn-

ing of the rudder is coincident with the vertical minimum internal diameter of the nozzle, and is so assembled that this axis of turning is coincident with the plane in which the tips of the propeller blades rotate.

The rudder is shown to be overhung from the transom or stern of the boat (it might be hung from a false transom recessed within the stern). A bearing-block 3 for the propeller shaft 8 is carried on a strut 4 that extends downward from the overhang of the stern. This strut, in accommodation to the further features of invention, is formed of two symmetrically shaped outwardly bowed plates that converge sternward to an edge 4', as clearly seen in Figures IV and V.

At the forward edge of strut 4 an auxiliary rudder 5, carried under the overhang of the boat, is mounted to swing on a vertical axis; i. e. perpendicular to the axis of the propeller shaft, and, as appears in Figure IV, the axis of swing of the auxiliary rudder 5 is, like the axis of swing of the main rudder 1, coincident with the vertical plane through the axis of propeller rotation. The auxiliary rudder 5 extends forwardly from its axis of pivoting, and beneath the overhang of the stern of the boat. It is of forwardly tapering shape, as best seen in Figure V, and, when in mid-position (Figure V), it forms with the strut 4 a structure of streamlined, hydrofoil shape. The sternward taper of the plates that form the strut is more abrupt than the gradual forward taper of the body of the rudder 5 itself.

The auxiliary rudder 5 is mounted upon a post 6, and the post 6 rests in and is rotatably borne in a seat 6' provided for it in the bearing block 3 of the propeller shaft.

The auxiliary rudder 5 is shown to be arranged wholly above the shaft 8 of the propeller, and is of such extent as to act in the upper half of the column of water that the advancing nozzle takes in. However, as hereinafter more fully described, and as shown in Figure VII, a duplicate part may be provided below the propeller shaft.

The auxiliary rudder assembly, including its stationary sternward continuation in the strut 4, is arranged to extend immediately forward of the intake end (forward end) of the nozzle 2, with sufficient clearance, however, to allow the nozzle to swing in horizontal plane throughout its proper range of turning.

The auxiliary rudder 5 is so built and organized as to be capable of swinging in unison with the swing of the main rudder 1. Each steering unit has its proper range—its proper steering angle—and the proper range of swing of the aux-

iliary rudder 5 is greater—approximately fifty per cent greater—than that of the unit comprising rudder 1 and nozzle 2. Of the latter, the proper range of swing is approximately 22° to either side from fore-and-aft position; of the auxiliary rudder the proper range is approximately 33° . This is indicated in Figure IV by the arcs *a* and *b*. Linkage is provided, as indicated at 7, and best shown in Figure VI, connecting the two rudder units 1, 2 and 5, such that, while unit 1, 2 swings through an angular range of $2m$, unit 5 swings through a range of $3m$, and further, that the units shall have permissible ranges of swing respectively through their proper ranges. The links 7 are connected at their forward ends to opposite ends of member 6a on the rudder post 6 and the rear ends are pivotally connected to a plate member 7a at the top of the rudder 1, and the differential movement is accomplished by reason of the rear ends of the links 7 being further from the center of rotation of the plate 7a than are the forward ends of the link 7 from the axis of rotation of post 6.

It is not necessary that the stern end of the auxiliary rudder (formed by the strut 4) be movable; by its rigidity it serves other useful ends; and it suffices that the forwardly extending portion 5 swing, to aid in steering.

In the forward travel of a boat equipped with the steering apparatus described, the action of the auxiliary rudder 5 tends to render the boat more immediately responsive to her helm; it is in backing, however, that the utility of the invention is greatest. When the propeller begins to turn backward, the Kort nozzle is of relatively small effect as a steering element, and (lacking the auxiliary rudder of the invention) the boat responds but slowly to her helm; but, the auxiliary rudder 5 being present, its effect at the beginning of backward movement is immediate and pronounced, and the boat responds accordingly. In consequence, the steering equipment of the invention is of peculiar value and advantage in the navigation of rivers and narrow and winding channels.

The construction shown in Figure VII is essentially the same as that shown in Figure I, except that the auxiliary rudder 5 has a counterpart 5a below the propeller shaft, and, accordingly, corresponding reference numerals are used to indicate corresponding parts. To provide the lower auxiliary rudder section, a portion 4a, conforming generally in contour to part 4, projects down from the bearing 3 and it has two forwardly projecting lugs 9 and 10. The upper lug 9 has a depending pin 11 thereon that enters the top of portion 5b or the rear of the rudder section 5a. A removable pin 12, held in place by nut 13, projects through the lower lug 10 into a lug 5c on the rudder section 5a. By removing nut 13, pin 12 may be dropped down, whereupon rudder section 5a may be lowered until part 5b is free of pin 11, thus enabling the rudder section 5a to be quickly removed. Outwardly bowed straps 14, bolted to sections 5 and 5a on each side face of the rudder, transmit turning motion from the upper to the lower section, while the outward bowing of the straps gives clearance for the propeller shaft, so that the arc of movement of the rudder 5—5a is not confined by the straps. The straps may be in line with the rudder post, but for clearness of illustration they are shown forwardly of the rudder post.

The drawings show the steering apparatus to include a single set of elements 1, 2, 4, and 5, 75

combined with a single propeller P, and all arranged on the center line of the ship. It will be understood that a boat may be equipped with a plurality of sets of the parts named, grouped as here described, and symmetrically arranged with respect to the mid fore-and-aft plane of the boat.

I claim:

1. Steering mechanism for propeller-driven ships comprising a nozzle element about the propeller movable in an arc about an axis substantially perpendicular to the axis of rotation of the propeller, a rudder element forwardly of the nozzle, said rudder element being pivotally supported at the aft end thereof, and means differentially coupling the rudder and the nozzle for concomitant operation through differing degrees of arc.

2. Steering mechanism for propeller-driven ships comprising a nozzle element about the propeller movable in an arc about an axis substantially perpendicular to the axis of rotation of the propeller, a movable rudder element forwardly of the nozzle, said rudder element being partially streamlined and being pivotally carried on a fixed rudder section with its pivotal axis adjacent the fixed rudder section, said fixed rudder section being immediately forward of the nozzle and of a shape which complements the streamline of the rudder, and means operatively connecting said movable rudder element and the nozzle.

3. In a ship propulsion and steering mechanism having a propeller shaft and propeller and having a nozzle element surrounding the propeller, said nozzle being movable about an axis substantially perpendicular to the axis of rotation of the propeller; a movable rudder element forwardly of the nozzle symmetrically disposed above and below the propeller shaft, said rudder element being pivotally supported at the aft end thereof for movement about an axis, substantially perpendicular to the axis of rotation of the propeller, and means differentially coupling the rudder and the nozzle for concomitant operation through different degrees of arc with the rudder element having an arcuate movement greater than the nozzle.

4. Steering apparatus for a boat wherein there is a nozzle encircling the propeller of the boat, the nozzle being movable in an arc about a vertical axis, the herein-described invention comprising an auxiliary rudder arranged forward of said nozzle and pivoted at its stern end for movement about a vertical axis, and means interconnecting the nozzle and the auxiliary rudder for turning them simultaneously in the same effective direction and to different degrees of arc.

5. Steering apparatus for a boat with overhanging stern and a propeller shaft extending beneath such overhang, and in combination with a rudder unit than includes a nozzle adapted to encircle a propeller borne by such shaft, the invention herein described which consists of a strut depending from such overhang and forward of said nozzle, a bearing block for the propeller shaft borne by said strut, and an auxiliary rudder mounted for turning upon an axis adjacent the forward edge of said strut and extending thence forwardly, the auxiliary rudder being in the stream flow from the nozzle when the propeller is operating in reverse, the auxiliary rudder being carried by a post seated for rotation on the said bearing block.

6. Steering apparatus for a boat with overhanging stern and a propeller shaft extending

beneath such overhang, and in combination with a rudder unit that includes a nozzle adapted to encircle a propeller borne by such shaft, the invention herein described which consists of a strut depending from such overhang and forward of said nozzle, a bearing block for the propeller shaft borne by said strut, and an auxiliary rudder mounted for turning upon an axis adjacent

the forward edge of said strut and extending thence forwardly, the strut being of sternward tapering horizontal section, the auxiliary rudder being a forwardly tapering horizontal section, the two last named members forming a unit of hydrofoil shape in horizontal section.

ALBERT J. DAWSON.
